(57) **CLAIM**

The ornamental design for a scoop, as shown and described.

DESCRIPTION

FIG. 1 is a perspective view of a scoop according to my new design;

FIG. 2 is a top plan view thereof;

FIG. 3 is a bottom plan view thereof;

FIG. 4 is a left side view thereof;

FIG. 5 is a right side view thereof;

FIG. 6 is a front view thereof;

FIG. 7 is a rear view thereof;

FIG. 8 is another perspective view thereof, but shown with the broken line subject matter longer in length;

FIG. 9 is another top plan view thereof;

FIG. 10 is another bottom plan view thereof;

FIG. 11 is another left side view thereof;

FIG. 12 is another right side view thereof;

FIG. 13 is another front view thereof; and,

FIG. 14 is another rear view thereof.

The broken lines illustrate portions of the scoop that form no part of the claimed design.

1 Claim, 14 Drawing Sheets
